IGNITION COIL

William F. Bergerd, Riverside, Frank G. Majer, Berwyn, and Harold E. Knopp and Lawrence E. Bennett, Chicago, Ill., assignors to International Harvester Company, a corporation of New Jersey

Application May 27, 1944, Serial No. 537,560

4 Claims. (Cl. 175—361)

1

This invention relates to an ignition coil. More specifically, it relates to improvements in induction coils and particularly to the type used for ignition in internal combustion engines. The principal object is to provide an improved induction coil structure entirely housed in an improved metallic casing. A more specific object is to provide an enclosure structure for induction coils which may be readily and permanently sealed without use of solder and objectionable means.

Another object is to provide an enclosure structure for induction coils consisting of two substantially cup-shaped portions which may be hermetically sealed together by securing flanges on the cup-shaped portions together.

The above objects and others which will be apparent from the detailed description to follow, are obtained by a construction such as shown in the drawing, in which

Figure 1 is an elevation view of a coil embodying the invention;

Figure 2 is a section taken through the center of the coil of Figure 1;

Figure 3 is a section taken on line 3—3 of Figure 2; and

Figure 4 is a detail view showing a modification.

Referring to Figures 2 and 3, an inner core structure 10 is formed from a plurality of thin metallic laminations running lengthwise of the core. As will be observed in Figure 3, a plurality of the laminations are stacked together in one direction with additional laminations 11 being fitted on each side. This construction leaves triangular shaped openings 12 at each corner and openings 13 along the flat dimension of the laminations when the core is inserted in a tube 14 of insulating material.

A secondary coil 15 of conventional construction is fitted over the tube 14. Said coil terminates spaced from the ends of the tube 14, said tube being also spaced from the ends of the core 10. A section 16 of paper insulation projects at each end of the secondary coil 15 for holding the coil in position, as will be hereinafter described.

Tubes 17 of insulating material surround the secondary coil 15. The primary coil 18 is wound around the insulating tubes 17. A layer of insulating material is wound around the outside

2

of the primary coil 18. A slotted sheet steel member 19 is fitted around the said insulating layer for carrying the outer portion of the magnetic path, the core 10 being the inside magnetic path.

Outside the slotted sheet steel member 19, two cup-shaped members 20 and 21 are closely fitted. Said cups directly contact the member 19. The member 20 has a rounded bottom portion 22 terminating in the conical flange 23. Said flange 10 is imbedded in a member 24 formed of any suitable insulating material. Said member is preferably formed of molded Bakelite with suitable asbestos or other heat-resisting fillers. The member 24 carries imbedded in proper position 15 a pair of primary terminals 25 and 26. In the usual process of manufacture the terminals 26 and the flange 23 of the member 20 would be molded into position during formation of the member 24. Bores 27 extending through a 20 portion of the terminals 25 and 26 and through portions of the member 24 provide means for leading the primary coil terminals 23 out of the coil and for electrically securing them to the terminals 25 and 26. Adjacent the center of the 25 coil the member 20 is provided with an out-turned flange 29.

As illustrated in Figure 2, the flange 29 is in alignment with and spaced from a similar flange 30 formed on the member 21. A gasket 31 between said flanges provides a sealing means when a securing member 32 is spun over the flanges 29 and 30. This construction may be varied as illustrated in Figure 4, which shows flanges 29' and 30' secured together by seam welding. The 35 flanges may be pressed into contact and welded together by a continuous seam around the coil without the generation of heat, which would adversely affect the coil structure.

The member 21 is provided with a curved bottom portion 31' terminating in a conical flange 32' which is imbedded in a member 33 formed of insulating material, preferably of a molded Bakelite or similar material. Said member is formed in the usual ridge 34 to provide a long 45 flow path and to prevent short-circuiting of the high-tensioned current. A metallic secondary terminal member 35 is imbedded centrally in the member 33 preferably during the molding operation. A metallic member 36 fitted in an internal bore or recess 37 formed in the member

33 is provided with a portion 38 which abuts the terminal member 35. The member 36 also abuts the end of the core 10. A similar member 39 fitted in a recess in the member 34 abuts the other end of the core 10. In the construction of this device the dimensions are so controlled that when the flanges 29 and 30 are secured together the members 39 and 36 firmly abut the ends of the core. One terminal of the secondary coil is secured to the contact member 40 by 10 any suitable means, the other end being in electrical contact with the housing structure.

Each of the members 24 and 33 are provided with a plurality of circular ridges 41. Said ridges are forced into the end of the paper insulation layers 16 so as to support the secondary winding endwise and, further, so as to make the paper around the ridges more dense and to give long leakage paths for the secondary current from the inside core to the outside slotted sheet metal wrapping just inside of the housing structure as formed by the members 20 and 21. The ridges 41 are cut away periodically as at 42 in staggered relationship so that transformer oil, with which the coil is filled, can work from the inside to the outside of the coil, thus giving complete filling over the coil surface.

All of the voids between the insulation and most of the space in the coil not occupied by solid matter are filled with insulating oil, which keeps out moisture and is a good insulation in itself. The spaces 12 and 13 around the core 10, previously referred to, permit circulation of the oil so that it may reach all parts of the coil. In the construction of the coil, after the flanges at the center have been hermetically closed or joined together, the coil is heated with vacuum applied through the terminal outlets after which hot transformer oil is allowed to fill the evacuated space. The coil assembly is then sealed at the terminals while at the elevated temperature. The improved coil structure, and particularly the enclosure or casing therefor, as above described represents a marked advance in coil construction from the standpoint of reliability and the fact that longitudinal seams and complicated joints are voided. Also, the use of solder is eliminated. The two members 20 and 21 are formed as drawn steel cups which may be made from the desired thickness of material. By a simple operation the flanges 23 and 32 can be readily formed, said flanges being properly shaped to give a good, hermetically bond with the molded members and also being of a shape to reinforce and strengthen said members. The center joint may be readily formed either by spinning a member around the flanges as shown in Figure 2, or by seam-welding as shown in Figure 4. The construction also assures firm support of the core 10 and of the winding within the core, particularly the heavy secondary winding which is held securely by the sections of paper insulation 16 into which the ridged portions 41 of the members 24 and 33 are imbedded.

Applicants claim as their invention all modifications in coil structure falling within the scope of the appended claims.

What is claimed is:

1. An ignition coil comprising a coil, an inner structure including a laminated metallic central core, concentric primary and secondary coils surrounding said coil and terminating spaced from the ends thereof, oil-flow passages extending from end to end of said structure, a slotted metallic sleeve surrounding said primary coil and a pair

of housing sections enclosing said inner structure, each of which includes a molded end structure having a recess in which said core extends and axially extending ribs engageable with the coil structure for positioning the same, said ribs being provided with interrupted portions to form oil passages for insulating oil-flow therethrough and through the first named oil passages, said housing sections also including metallic cups having flanges imbedded in the end structures, said metallic cups being tightly fitted over said slotted sleeve and being provided with means intermediate the ends of the sleeve for securing the sections hermetically together.

15 2. An ignition coil comprising a coil, an inner structure including a laminated metallic central core irregular in cross section, an insulating tube fitted around said core in contact therewith, the irregular shape of the core providing passages extending lengthwise between the core and the tube, a secondary coil surrounding said core and terminating spaced from the ends thereof, a primary coil surrounding said secondary coil and a housing enclosing said inner structure and including a casing and a molded end structure at each end thereof having a recess in which said core extends and concentric radially spaced axially extending ribs engageable with the coil structure for positioning the same, said ribs having interrupted portions to provide openings for the flow of insulating oil therethrough and to the passages along the center core.

30 3. An ignition coil comprising a coil, an inner structure including a laminated metallic central core irregular in cross section, an insulating tube fitted around said core in contact therewith, the irregular shape of the core providing passages extending lengthwise between the core and the tube, concentric primary and secondary coils surrounding said core and terminating spaced from the ends thereof, and a pair of housing sections enclosing said structure each of which includes a molded end structure having a recess in which said core extends and concentric radially spaced axially extending ribs engageable with the coil structure for positioning the same, said ribs having interrupted portions to provide openings for the flow of insulating oil therethrough and to the passages along the center core, said housing sections also including metallic cups having flanges imbedded in the end structures and provided with means for securing the sections hermetically together.

35 4. An ignition coil comprising a coil, an inner structure including a laminated metallic central core irregular in cross section, an insulating tube tightly fitted around said core in contact therewith, the irregular shape of the core providing passages extending lengthwise between the core and the tube, concentric primary and secondary coils surrounding said coil and terminating spaced from the ends thereof, a slotted sleeve surrounding the outer coil and a pair of housing sections enclosing said inner structure, each of which includes a molded end structure having a recess in which said core extends, and concentric radially spaced axially extending ribs engageable with the coil structure for positioning the same, said ribs having interrupted portions to provide openings for the flow of insulating oil therethrough and to the passages along the center core, said housing sections also including metallic cups having flanges imbedded in the end structures, said metal cups being tightly fitted over said slotted

sleeve and being provided with means intermediate the ends of the sleeve for securing the sections hermetically together.
